UNITED STATES PATENT OFFICE

LOUIS G. FREEMAN, OF CINCINNATI, OHIO, ASSIGNEE TO THE LOUIS G. FREEMAN COMPANY, OF CINCINNATI, OHIO, A CORPORATION OF OHIO

SIDE TACK PULLER

Application filed September 7, 1923. Serial No. 661,450.

My present invention is an improved tack pulling machine for use in operating upon boots and shoes during their construction.

In the manufacture of boots and shoes, particularly welt shoes, it is necessary to remove the lasting tacks prior to the stitching or other permanent fastenings. In my prior patents I have illustrated and described several machines for performing tack removing operations, but in my development of machines for this purpose, I find that it is most important to have a tack removing machine, so constructed and arranged as to provide a wide and free range of manipulation of the shoe adjacent the tack fork or other tack removing instrumentality, and for this purpose it is important that the operator have an unobstructed view of the tack removing action. As it is of vital importance to supply a work rest or work holder against which the shoe may be held, guided, positioned and manipulated, which ordinarily is somewhat below, although necessarily closely adjacent, the tack removing fork, it has been extremely difficult to construct such devices and yet permit a wide range of manipulation of the shoe and an unobstructed view by the operator as the shoe is held adjacent the tack removing fork. In my present machine I have so constructed and arranged the same as to maintain the shoe holder and guard properly positioned and adjustably secured in its shoe holding position adjacent to and somewhat below the tack fork, thereby to give wide range of manipulation to the operator, and yet to secure a firm solid support and adjustment from above the tack removing fork. The importance of this feature will be appreciated when it is realized that the operator must frequently "dig in" for a tack which has been driven home and remove same and yet without scuffing, marring or cutting the shoe and upper materials from which the tack is drawn. Particularly at the shank of the shoe and other portions it is important to enable the operator to twist, turn, and manipulate the shoe in a variety of ways, to facilitate removal of the lasting tacks. When it is also appreciated that these tack removing forks are run at high speed, the driving shaft usually

operating at the rate of several thousand R. P. M., it will be seen that the importance of adjustment, manipulation, full view, and ease afforded for manipulating the shoe is of vital necessity. My present invention includes means which will simultaneously adjust the guards for the tack removing fork, the hold-down for the shoe, and the eye-guard, both laterally, vertically and otherwise, by a single operation. I accomplish this desirable feature by affixing the guards and devices to a movable and adjustable head supported to and adjustably secured to the top of the machine, having the scuffing guard and hold-down for the shoe depending therefrom. Thus by a single movement I secure an adjustment of these devices laterally with regard to the tack fork, as well as vertically with regard to the relative position and clearance for the fork, guard and shoe. Furthermore, this adjustable support is positioned out of the way of the shoe and operator when the latter is manipulating the shoe to remove the tacks.

A still further feature of the present invention consists in the provision of a large reservoir of oil and means to supply the same to the driving shaft, moving parts and fork carrying bar. As such tack removing machines usually depend upon a reciprocating and oscillating bar, it is practically impossible to provide a fixed and oil-tight bearing through which the bar runs, owing to the oscillatory path of movement requisite for the tack removing fork. I have, in the present machine, overcome this difficulty, and have provided means which will supply a large amount of oil to the entire moving parts, and yet will prevent the same from being thrown out along the line of the oscillating tack fork carrying bar and damage the shoe. Preferably I employ a plurality of oil retaining means for this purpose, which will yet permit free movement of the oscillating bar, as explained. The provision of a substantial oil supply in a machine of this kind is a distinct novelty and I wish to claim the same broadly. Other important advantages, details and novel combinations of parts will

100

be hereinafter more fully pointed out and claimed.

In the accompanying drawings illustrating the preferred embodiment of my invention,

5 Fig. 1 is a side elevation;

Fig. 2 is a fragmentary vertical sectional elevation on the line 2—2 of Fig. 1;

Fig. 3 is a plan view;

Fig. 4 is a front elevation of Fig. 3;

10 Fig. 5 is a front elevation of a modified form of guard employed;

Fig. 6 is a detail sectional view showing the relative position of a tack fork, a shoe from which the tack is to be removed, and a scuffing guard;

15 Fig. 7 is a plan view of a tack fork;

Fig. 8 is a sectional view on the line 8—8 of Fig. 7, and

Fig. 9 is a detail of a modified form of scuffing guard.

Referring to the drawings, 10 designates a base or pedestal to the lower end of which is rotatably mounted a shaft 11 carrying a driving pulley 12 and driven from any suitable source of power. Formed integral with the base or pedestal 10 or secured thereto in any suitable manner and extending upwardly therefrom to any convenient height is a head 13, this head being hollow and having a portion 14 thereof extending upward and laterally with respect to the base or pedestal 10. Intermediate the ends of the vertical portion of the head 13 is a diaphragm 15 which forms the bottom of an oil chamber or reservoir 16 containing a body of oil or other lubricating fluid 17. Screwed into the wall of the head 13 and communicating with the oil chamber or reservoir 16 is an oil gauge 18 and by means of which the level of the oil in the reservoir 16 may be readily determined. This oil gauge 18 has connected therewith a cock 19 for the purpose of drawing off surplus or used oil.

Secured to the side wall of the head 13 in any desired manner and extending inwardly to a point within the oil chamber or reservoir 16 is a head bearing 20. In the head bearing 20 is a longitudinal passage that lies parallel with the axis of the shaft 11 and the head bearing 20 extends laterally from the head 13 on the same side of the pedestal or base 10 as the pulley 12. In the longitudinal perforation in the head bearing 20 is a renewable bronze bushing 21 in which is rotatably mounted a crank shaft 22 which, because of the construction above described, lies parallel with the drive shaft 11. Secured to the crank shaft 22 is a grooved balance pulley 23, the groove 24 of which is in vertical alinement with the corresponding groove in the drive pulley 12 and passing over the pulleys 12, 23 is a driving belt 25 by means of which rotary motion is imparted to the crank shaft 22 by the drive shaft 11. Secured to the crank shaft 22 by pin 26 is

a balance 27 which, as the crank shaft rotates, dips into the body of oil 18. Other parts of the mechanism may be effective to splash the oil over the actuating mechanism in lieu of the splashing action of the balance 27 or in addition thereto, dependent, of course, upon the level of oil in the reservoir. The head bearing 20 is provided with a plurality of oil ways 28 leading to the crank shaft 22 through the renewable bronze bushings 21 and oil cups 29 are arranged at the receiving end of such oil ways 28. The head portion 14 is, as shown in Fig. 1, cut away and in this cut away portion is fitted a closure plate 30 which is held in position on the head portion 14 by means of a spring clamp 31 pivotally secured to the top of the head portion 14 in any desired manner. Guide ways are formed in the interior of the head portion 14 in which is slidably mounted a puller bar 32, the rear end of which is split, as shown at 33, the split end clamping over a bronze bushing 34 and holding such bronze bushing by means of a screw 35, the bronze bushing being a fit on an eccentric crank pin 36 on the end of the crank shaft 22. A rear cap 37 fits over one of the bearings in which slides the puller bar 32 and is held in position thereon by screws 38 while the front cap 39 fits over the front bearing for such puller bar and is secured in position by screws 40. Secured to the interior of the head portion 14 by screws 41 is a pivot bar 42 to which is pivotally mounted one end of a pivot bar link 43, the other end of this link being pivotally attached to the puller bar 32, as clearly shown in Fig. 1. As the crank shaft 22 rotates, the running balance 27 splashes a portion of the oil 17 out of the reservoir 16 and forward toward the front of the head portion 14, thus lubricating the puller bar 32 and the bearings in which the same slides, as well as lubricating the pivot points of the pivot bar link 43. Lubrication almost to the point of excess is necessary, due to the great speed at which the crank shaft 22 revolves and therefore no matter how tight the bearings may be between the front cap cover 39 and the puller bar 32, some oil will work through and there is, therefore, danger that the oil will fly out onto the shoes from which the tacks are being removed. To obviate this danger, I have provided, adjacent the rear end of the front bearing and the front cap 39 for the same, a partition wall shown at 46 which I have found an efficient means for preventing leakage of oil out through the front of the head portion 14. The front end of the puller bar 32 is provided with a slot 47 that makes an angle with the length of the puller bar 32 and in this slot is mounted the shank end of a tack fork 48. Securely holding the tack fork in any adjusted position in the slot 47 is a plate 49 which is in turn held in position on the puller bar 32 by the screws 50.

Secured to the top of the head portion 14 by bolts 51 is a top arm 52, this top arm being provided with a plurality of elongated slots 53 through which the bolts 51 pass and by means of which it is possible to move the arm relative to the head portion 14. The outer end of the top arm 52 is enlarged at 54 and this enlargement is provided with a slot 55 in which is slidably mounted the guard arm 56, a clamp 57 secured to the front of the enlargement 54 by bolts 58 securely holding the guard post in any adjusted position along the length of the slot 55. The clamp 57 not only acts to hold the guard arm 56 in adjusted position, but acts also as a holding device for a shield 59, clamping jaws 60 being provided at the lower end of the clamp 57 for this purpose. The shield 59 may be semi-circular in shape, as shown in Fig. 4, and 20 may be of heavy plate glass or may be of the shape shown in Fig. 5 which has a portion 61 thereof cut away to allow the shield to be made of other material such as iron while yet permitting the operator to look downward upon the tack fork without danger of having tacks thrown upward into his face.

Secured to the guard arm 56 in any suitable manner is a scuffing guard 62 in which works the tack fork 48 and this scuffing guard 30 has formed integral therewith a side wing 63 separated from the main portion by heel 70 which acts to protect the upper of a shoe being worked upon from damage by the tack fork travelling in its orbit. At the side of 35 the scuffing guard 62 (where it is fastened) there is an extended side 64. The extended side 64 performs two functions, one of which is to hold down the upper next to the tack when pulling tacks that are driven deep, and 40 the other is to enable the operator to bring the shoe into operative position with respect to the tack fork quickly and without risk of the shoe slipping from its position and becoming damaged. The tack fork 48 is made 45 in different widths to suit different conditions and the scuffing guards are made in widths to suit the particular width of tack fork. Both the scuffing guards 62 and the tack forks 48 are made right and left handed 50 to suit right and left handed operators. The placing of the scuffing guard in position supported from above the work is a decided advantage in devices of this character. The horizontal adjustment of the scuffing guard 55 62 is made through the top plate 52 while, as described above, the vertical adjustment of said scuffing guard 62 is provided for by means of the plate 57 and bolts 58. No adjustment is required for the guard plate 59.

60 In addition to the tack forks 48 being made either right or left handed and of any desired width, I find it of considerable advantage to make the forward serrated edge of such tack fork lie at an angle to the plane 65 in which the tack fork rotates, this feature

being clearly brought out in Figs. 6 and 7 where, in Fig. 6, the dotted closed line 65 shows the orbit taken by the tack fork and Fig. 7, in plan, shows the angle or rake the forward serrated edge of the tack fork makes with the plane in which the tack fork works. Referring to Fig. 8, there is shown a section of one of the teeth 66 of the tack fork 48 and it will be noted that each of said teeth, in section, is substantially trapezoidal in shape to better facilitate the engagement of such teeth with the tack 67 to be removed from the shoe structure 68 being built on the last 69.

The operation of my improved device is as follows, it being assumed that such device is constructed and assembled in the manner above described. The reservoir 16 being filled with oil 17 to the desired depth so as to allow the balance 27 to dip into the same and splash oil up through the forward part of the head 14, the tack fork 48 and the scuffing guard 62 being adjusted to operate to remove tacks from shoes 68, power is thrown onto the main shaft 11 which, through the belt 25, imparts rotary motion to the crank shaft 22 and the crank 36 thereon will cause a reciprocatory motion of the puller bar 32. The reciprocatory motion imparted to the puller bar 32 is modified by means of the pivot bar link 43 and the forward end of the puller bar, as represented by the operating serrated end of the tack fork 48, is forced to describe a path represented by the dotted line 65, the movement of the front of the tack puller 48 taking place in the direction of the arrow shown in Fig. 6. The tack pulling operation is performed in the usual manner, the operator passing the shoe 68 on the last 69 transversely of the line of travel of the tack puller 48 and the rapidly moving tack fork engaging with the tack 67 pulls them out of the shoe. The side wing 63 prevents injury to the shoe by the tack fork and the extended side 64 holds down the upper next to the tack, when pulling tacks, and enables the operator to bring the shoe into operative position without risk of slipping from position and damaging the shoe, while the heel 70 holds the upper down on the last 69 while the tacks are being pulled. The scuffing guard as a whole prevents scuffing of the shoe uppers by the tack fork 48. The partition wall 46 prevents oil working out of the head 14 and flying onto the shoe.

As a further safeguard to prevent any oil that may work out on bar 32—especially the top and bottom faces thereof—from flying off and soiling the shoe being worked on, I place a guard 71 on the puller bar 32 at a point just outside the opening in the head through which the puller bar 32 passes. The face of this guard 71, adjacent the end of the portion 14 of the head 13, is concaved, as indicated at 72. This concave portion 72 guides any oil, that may be creeping along the bar 120

32, downwardly and into a receptacle 73 that is secured to the bottom of the portion 14 of the head 13 by screws 74. The oil supply is preferably sufficient for the continuous operation of the machine during an entire month, thus insuring the full efficiency of the machine without having it stopped for oiling, and without endangering the life of the machine through careless operators neglecting to oil the moving parts when needed.

10 In Fig. 9 I have illustrated a modified form of scuffing guard in which the extension 64 is made separate from the portion 62, said extension 64 being adjustably mounted on the portion 62 by screws 75. On the upwardly extending lower edge 76 is provided a cut-away portion 77 in which is housed a rotatable mounted roller 78 which materially reduces the friction when the shoe is slid laterally along the guard while pulling tacks.

15 Considerable difficulty is experienced in holding the tack fork 48 from slipping in its holder, and this difficulty is obviated by forming serrations 79 in one face of the tack fork, 20 which serrations engage with corresponding serrations (not shown) in the clamping plate 49.

25 While I have necessarily shown and described the preferred embodiment of my invention somewhat in detail, it is to be understood that I may vary the size, shape, and arrangement of parts comprising my invention within wide limits without departing from the spirit of the invention. The important 30 features of having an adjustable head carrying the various guards, and all adjusted, both vertically and longitudinally, with relation to the fork, irrespective of the size, length, or dimension of the tack removing fork 48 is of very considerable importance, particularly as these forks are often changed and shifted, and the time saved is an important element. The entire machine is self-contained and of simple compact construction, permitting the widest possible 35 range for manipulating the shoe in under, and around the guard and fork. The large oil supply insures the running of the machine, and permits greatly increased speed of operation, with perfect safety and efficiency, and yet while supplying for this purpose a large 40 volume of oil, protects and guards the shoe from damage by throwing of oil. The arrangement whereby I have supplied all the 45 tack removing instrumentalities, the shoe guard or guide, the tack guard or guide, and the other mechanism positioned at one side of the line of tacks to be removed and preferably opposite the operator, is a novel construction of great advantage and importance, 50 as it enables the operator to have a clear, uninterrupted vision of the exact point of tack removal. This increases the ease, speed and efficiency of the tack removing operation, 55 greatly facilitates the manipulation of the

shoe especially for "digging in to a deeply set tack and enables the operator, at all times, to see the work. In prior machines of this kind with the guard, some member of the machine, such as the shoe rest, or a tack-engaging member was positioned between the operator and the actual point of tack removing. Therefore such prior machines did not have a full and uninterrupted view of the actual point of tack removal. Furthermore, in most 70 prior machines the tack lifting, removing or pulling devices or forks were arranged to move toward a work rest, usually away from the position of the operator and sometimes utilizing the tack-engaging edge of a work rest to aid in effecting the tack pulling. My machine has the working or moving tack lifting devices movable across the work rest and toward the line of tacks to be removed and hence toward the operator. Thus I have 75 provided a construction eliminating all parts of the machine from blocking the operator's vision. This feature of having a portion of the path of travel of the tack pulling devices movable across the work rest and toward the 80 tack-engaging edge is thus of importance and I wish to claim the same herein broadly. 85 With the further addition of a transparent guard to stop flying tacks from injuring the operator, I have thereby provided a machine 90 of this type wherein the actual point of contact between the tack pulling devices and the lasting tacks can be and is in the direct line of vision of the operator, a distinct novelty in this art.

95 Having thus described my invention, what I claim as new is:

1. In an improved tack pulling machine, the combination of a single tack fork, means for imparting orbital motion in a vertical 105 plane to the working end of said tack fork, a scuffing guard associated with said tack fork, and having a portion positioned under the fork and in advance of the movement of the fork to the line of tacks, and a projection 110 on said scuffing guard to protect the upper of a shoe being worked upon from damage from the tack fork.

2. In an improved tack pulling machine, the combination of a single tack fork, means for imparting orbital motion in a vertical 115 plane to the working end of said tack fork, a scuffing guard associated with said tack fork and having a portion positioned under the fork and in advance of the movement of the 120 fork to the line of tacks, a projection on said scuffing guard to protect the upper of a shoe being worked upon from damage from the tack fork, and means on said scuffing guard for holding the upper of a shoe down while 125 tacks are being pulled from the shoe.

3. In an improved tack pulling machine, the combination of a head, a tack fork mounted in and extending forwardly of the head, a top plate adjustably mounted on said head, 130

a substantially vertical guideway in said top plate, a scuffing guard mounted in said guideway for vertical movement therein and with respect to the tack fork, and means for holding the scuffing guard in any adjusted position in said guideway and with respect to the tack fork while maintaining a portion of said guard in position under the path of travel of the fork when approaching the line 10 of tacks.

4. In an improved tack pulling machine, the combination of a head, a tack fork slidably mounted therein and extending forwardly thereof, a top plate mounted on said head, 15 means permitting adjustment of said top plate longitudinally of the head, a scuffing guard, means for adjustably mounting said scuffing guard for vertical movement in the top plate, and a guard located above said tack 20 fork.

5. In an improved tack pulling machine, the combination of a head, a tack fork slidably mounted in and extending forwardly of the head, a top plate on said head, means 25 for adjusting said top plate longitudinally of the head, a scuffing guard, means for adjustably mounting said scuffing guard in vertical position in the top plate, and a guard secured to the top plate and above the tack 30 fork.

6. In an improved tack pulling machine the combination of a head, an oil reservoir formed therein, a puller bar mounted in said head, means for imparting a combined forward and upward pulling movement to the forward end of said puller bar, means for throwing oil from said reservoir into the forward part of said head, said machine being constructed and arranged to prevent the oil 40 thrown into the forward part of said head from reaching the work.

7. In an improved tack pulling machine, the combination of tack pulling means, guiding and guarding means for the shoe and 45 tack pulling means, an oil reservoir, devices to supply oil to the moving parts, said machine being constructed and arranged to prevent the oil supplied to the moving parts, from reaching the work.

50 8. In an improved tack pulling machine, a scuffing guard, and an upper smoothing roller mounted thereon and lying in one face thereof.

55 9. In an improved tack pulling machine, the combination of a supporting head, a puller bar slidably mounted in and extending forwardly in front of said head, a tack fork secured to the front end of said puller bar, 60 means for imparting a combined slideable and rotary movement to the puller bar thereby to impart a substantially orbital movement to the tack fork, a plate adjustably secured to the top surface of the head and 65 extending forwardly therefrom, and a scuff-

ing guard permitting unobstructed view of the tack fork and the work.

10. In an improved tack pulling machine, the combination of a head, a tack fork, and a scuffing guard mounted on said head and 70 operatively associated with each other, said tack fork and scuffing guard being mounted to present an unobstructed view of the work, and a guard mounted on the head to prevent tacks drawn from the shoe from injuring the 75 operator, while permitting unobstructed view of the tack fork and the work.

11. In an improved tack pulling machine, the combination of a head, a reciprocating puller bar mounted therein, means for imparting a combined slideable and rotary movement to the end of the puller bar, a single tack fork secured to one end of the puller bar, a scuffing guard associated with the tack fork, 80 and means for adjustably securing the scuffing guard in rigid position with respect to the tack fork.

12. In an improved tack pulling machine, the combination of a tack fork and a scuffing guard adjustable vertically and longitudinally with respect to the tack fork, and a beveled side plate formed on said scuffing guard to 85 clear obstructions and to enable the operator to manipulate the shoe being worked on to extract deep seated tacks.

13. In an improved tack pulling machine, a scuffing guard, a tack puller associated therewith, and movable longitudinally thereof in a vertical plane, an anti-friction roller mounted at one edge of the guard, the axis of the roller lying in a plane forming an angle with the plane of movement of the tack fork, the surface of the roller extending outwardly beyond the surface of the scuffing guard.

14. In an improved tack pulling machine, the combination of a tack fork and a scuffing guard operatively associated therewith having a side guard projecting therefrom with its lower edge extending upwardly and forwardly from the lower face of the scuffing 100 guard for permitting manipulation of the shoe during the tack pulling operation.

15. In an improved tack pulling machine, tack pulling means movable in a line of movement toward the operator during the tack pulling operation, and a transparent guard positioned in front of the tack pulling means and between the operator and the tack pulling means, whereby said guard protects the operator from flying tacks while permitting 115 the operator to view the work.

16. In an improved tack pulling machine, the combination of tack pulling means, guiding and guarding means for the shoe and tack pulling means, said tack pulling means being 120 operable in a line of movement toward and from the operator and pulling the tacks from the work in its movement toward the operator, a transparent guard positioned between the tack pulling means and the operator and so 125 130

arranged as to permit free unobstructed view of the work during operation, while protecting the operator from possible injury from flying tacks.

17. An improved tack pulling machine having in combination tack pulling means, means to protect the work from said tack pulling means and a projection on said protecting means to guide the work, and mechanism to effect relative movement of the tack pulling means across a portion of the protecting means toward the tacks to be pulled.
18. An improved tack pulling machine having in combination tack pulling means, adjustable guiding means and guarding means for the work, said guiding means projecting from the guarding means, and mechanism to effect relative movement of the tack pulling means across a portion of the guiding and guarding means toward the tacks to be pulled.
19. An improved tack pulling machine comprising tack pulling means, an adjustable work rest having a guiding edge and a guarding portion, said edge being disposed forwardly at an angle with respect to said guarding portion, said rest being positioned under a portion of the path of movement of the tack pulling means in combination with mechanism to produce relative movement of the tack pulling means across said work rest to engage and pull tacks positioned adjacent the said guiding edge of the work rest.
20. An improved tack pulling machine having movable tack engaging devices and a work rest co-operating therewith, means permitting relative adjustment of said devices and work rest, said work rest having a guide portion and a guard portion arranged to guide and guard the work along the line of tacks to be removed, said guide portion being disposed at an angle forwardly from said guard portion, and mechanism actuating the tack removing means across the work rest to approach the line of tacks.
21. An improved tack pulling machine having movable tack engaging devices and a work rest co-operating therewith, means permitting relative adjustment of said devices and work rest, said work rest having a guide portion and a guard portion arranged to guide and guard the work along the line of tacks to be removed, said guide portion being disposed at an angle forwardly from said guard portion, and mechanism actuating the tack removing means across a portion of the work rest to approach the line of tacks to pull tacks adjacent said guide portion.
22. A tack pulling machine having in combination tack pulling means and actuating mechanism therefor, a casing forming an oil reservoir and enclosing said mechanism, said mechanism having means to splash oil over said actuating mechanism during operation thereof, thereby to bathe the same in oil, and

means to prevent the oil thus splashed from reaching the work.

23. A tack pulling machine having in combination tack pulling means and actuating mechanism therefor including a puller bar, work guarding means adjacent a portion of the path of movement of said tack pulling means, a casing forming an oil reservoir and enclosing said actuating mechanism, said puller bar being reciprocable in said casing, said mechanism having means adjacent one end of the puller bar to splash oil within the casing during operation of the mechanism thereby to bathe the same in oil, and means to prevent the oil thus splashed from reaching the work and work guarding means.

24. A tack pulling machine having in combination tack pulling means and actuating mechanism therefor including a puller bar, a driven crank connected to one end of said puller bar, a casing forming an oil reservoir and enclosing the crank and major portion of said puller bar, said puller bar being reciprocable in said casing, and said mechanism having means adjacent said crank to splash oil over the puller bar and associated mechanism thereby to bathe the same in oil, and means to prevent the oil thus splashed from reaching the work.

25. A tack pulling machine having in combination tack pulling means and actuating mechanism therefor, a casing forming an oil reservoir and enclosing said actuating mechanism, said mechanism having means to splash oil within the casing during operation thereof thereby to bathe the actuating mechanism in oil, said casing having a partition wall to prevent oil from escaping to the work.

26. A tack pulling machine having in combination tack pulling means and actuating mechanism therefor including a puller bar, a driven crank connected to one end of said puller bar, a casing forming an oil reservoir and enclosing said crank and the major portion of said puller bar, said puller bar being reciprocable in said casing, said mechanism having means adjacent said crank to splash oil within the casing thereby to bathe the puller bar and associated mechanism in oil, and a guard on the puller bar to prevent oil from creeping along the bar to the work.

27. A tack pulling machine having in combination tack pulling means and actuating mechanism therefor including a puller bar, a driven crank connected to one end of said puller bar, a casing forming an oil reservoir and enclosing said crank and the major portion of said puller bar, said puller bar being reciprocable in said casing, said mechanism having means adjacent said crank to splash oil over the puller bar and associated mechanism thereby to bathe the same in oil, said casing having a partition wall and said puller bar having a guard to prevent oil from escaping to the work.

28. A tack pulling machine having in combination tack pulling means and actuating mechanism therefor, a casing forming an oil reservoir and enclosing said mechanism, said mechanism having means to splash oil within the casing during operation of the mechanism, thereby to bathe the same in oil, said machine being constructed and arranged to prevent the oil splashed over the actuating mechanism during operation thereof in the casing, from reaching the work.

5
10 In testimony whereof, I have signed my name to this specification.

LOUIS G. FREEMAN.
